EXPANSION PULLEY

Jacob R. Hertenstein, Nashville, Tenn., assignor
to Nashville Machine and Supply Company,
Nashville, Tenn., a corporation of Tennessee

Application June 25, 1932. Serial No. 619,177

4 Claims. (Cl. 64—8)

My invention relates to expansion pulleys of the type in which the driving member consists of an expansible elastic rim which is connected to the hub member in such manner that it may be expanded and contracted to vary its engagement with the drive belt, such as the expansible pulley shown and described in Wardwell Patent No. 690,494, dated January 7, 1902. While my invention may be used for various purposes, it is particularly useful in machines for driving the spindles upon which are mounted what are termed in the trade "cone cores" for winding strands of textile materials, particularly rayon, in winding machines used in the textile industry. 10
15 In machines in common use for the purpose indicated, the most common practice is to use what are termed "gainer" pulleys, with expansible rims arranged to cooperate with flat belts arranged to drive pulleys on the spindle shafts, such as the Wardwell pulley above mentioned, but these flat belts are open to certain objections by reason of which they are not entirely satisfactory. A drive of this kind lays five or six threads rather too close together on the cone 20 core, and the next turn is spaced a considerable distance from the other threads. As a result of the threads being laid too close together, they occasionally "snarl up" when being unwound at the knitting mills which buy and use the wound rayon. This results in inconvenience, loss of time and defective work at the knitting mill, and loss to the producer of rayon in replacing defective cones. The inherent defect in this drive is believed to be due to a difference in tension on the 25 driving and slack side of the belt which takes place until a slippage equalizing the tension occurs, and this results in a periodical wide spacing in the turns of the thread being wound.

A positive gear drive for rotating the cone cores has been tried, but this is objectionably expensive, and is so positive in uniformly spacing the turns of the thread that each thread is laid directly on top of a turn beneath, without any "lead". This materially reduces the amount of rayon that can be wound on each cone core. The geared drive is furthermore not adjustable.

The principal object of the present invention is to enable the spindles of the cone cores to be driven by means of a relatively narrow belt having inclined side faces, commonly referred to as V-belts, which shall be free from the objectionable slippage and irregularity inherent in flat belts, and which also shall be free from the objections incident to a positive gear drive. It has been found that the V-belt drive to which my

present invention relates gives a better lay of the thread than either the usual flat belt or the gear drive, because the equalization of belt tension or "slip" seems to take place continuously, or substantially continuously, rather than intermittently, as in the case of the flat belt in which no slippage occurs while five or six turns of thread are being laid and all the slippage then takes place at once. The V-belt apparently slips sufficiently to prevent the threads from being wound one immediately over the other in successive layers, and lays the threads far enough apart so that they will not snarl when unwound from the cone cores.

I attain the object of my invention and accomplish the ends in view by a simple, efficient and inexpensive construction of the rim of a gainer pulley adapted to cooperate with a V-shaped belt as hereinafter fully described, and in practice my novel driving device, so constructed, has been found to give very superior results. The essential elements of my invention are herein-after more particularly pointed out in the appended claims.

In the drawing, Figure 1 is a diametrical section of a pulley embodying my invention.

Fig. 2 is a side view of the same shown connected by a V-shaped belt with a pulley on a driven shaft, such as the cone core shaft of a winding machine; and

Fig. 3 is a perspective of that one of four pins used to expand the rim of the pulley which is specially formed to restrain it from rotation upon the hub.

Like reference characters indicate like parts in all the figures of the drawing.

Describing now in detail the construction of my novel expansion pulley, the hub 1 of the pulley is secured to the pulley shaft, driven in any suitable manner. This hub consists of an exteriorly threaded central portion 2 connected at one side to an annular outer portion 3, which latter is formed with radial bores, in the present instance four in number, arranged to receive pins,—three of them marked 4 and one marked 10 on the drawing,—having their inner ends beveled in such manner as to cooperate with the outer coned face of an interiorly threaded adjusting sleeve 5 mounted on the threaded portion of the hub and extending into the space between such threaded portion and the annular outer portion. This adjusting sleeve is provided with a knurled end 6 by which it may be turned to force the pins 4 and 10 outwardly, or permit them to shift inwardly.

The outer ends of these pins are headed, and the outer faces of the heads shouldered so as to seat non-rotatably in a channel cut in the inner face of the split rim member 7 hereinafter described, so that the beveled inner ends of the pins will at all times be maintained in cooperative relation to the coned face of the adjusting sleeve and so that the split rim will be held in place on the hub members thus far described and restrained from axial displacement.

The split rim 7, to which my invention more particularly relates, is formed of spring metal and includes an inner spring section 8 extending continuously around the hub from its ends at the transverse split of the rim marked 9, and is formed with a central channel on its inner face, as above described. To prevent rotative slippage of the rim, the head of one of the pins, in the present instance the one marked 10, opposite the gap 9 (see Figs. 2 and 3) is formed with a recess adapted to receive a rib 11 extending across the channel at that point. Extending outwardly from the spring portion 8 of the rim are two series of arcuate flange sections 12 which are arranged in opposite divergent relation and together form a substantially continuous belt-receiving channel adapted to receive the V-shaped belt 13 which transmits power to the driven pulley 14 on the bobbin shaft. It will be noted that the spring section of the rim is flat and thin, whereby maximum flexibility and resiliency is attained, and that the bases of the flange sections stand between the center line of the rim and its outer edges, so as to provide a proper belt-receiving channel for the relatively thick and narrow belt. It will also be noted that the slots or gaps between the flange portions 12 of the belt groove permit the rim member to expand evenly and in some measure they also increase the gripping engagement between the belt and pulley. It is obvious that as the belt wears or stretches the spring rim can be expanded or allowed to contract through its inherent resiliency to adjust to a nicety its engagement in the channel of the pulley rim, and a much improved efficiency and regularity of function of the driving connection is thereby attained, as compared with any other form of driving device heretofore employed.

50 I claim:

1. In an expandible pulley including a hub member and a series of radial pins slidingly mounted in said hub member and means for equally shifting said pins radially, a transversely split rim member connected with the outer ends of said radial pins and formed with a spring inner section, and two series of arcuate flange sections arranged in opposite divergent relation together forming a substantially continuous belt-receiving channel adapted to engage a V-shaped belt, whereby expansion of the spring inner section of said rim member will vary the effective diameter of the belt-receiving channel formed by said arcuate flange sections.

80

2. In an expandible pulley having a hub member, a transversely-split rim member connected with said hub member, said rim member being formed with a spring inner section and two series of arcuate flange sections arranged in opposite divergent relation together forming a substantially continuous belt-receiving channel adapted to engage a V-shaped belt, means for expanding said rim member, the expansion of the spring inner section of said rim member acting to vary the effective diameter of the belt-receiving channel formed by said arcuate flanged sections, and means for restraining movement of said rim member in an axial direction.

85

3. In an expandible pulley having a hub member, a transversely-split spring metal rim member connected with said hub member, said rim member being formed with a flat thin inner section and two series of arcuate flange sections integral at their base with said inner section and arranged in opposite divergent relation together forming a substantially continuous belt-receiving channel adapted to engage a V-shaped belt, means for expanding said rim member, the expansion of the spring inner section of said rim member acting to vary the effective diameter of the belt-receiving channel formed by said arcuate flanged sections and means for restraining movement of said rim member in an axial direction.

100

4. An expandible pulley structure according to claim 3 in which the bases of said flange sections are formed severally intermediate the center line of the rim and the outer edges of said rim.
